COMBINED TOILET ROLL TISSUE DISPENSER AND HOLDER

William Hubiak, Albion, Pa.

Application May 27, 1955, Serial No. 36,259

Term of patent 14 years

(Cl. D4—3)

Fig. 1.

Fig. 2.

Fig. 3.

Fig. 4.

What I claim as new is:

An ornamental design for a combined toilet roll tissue dispenser and holder, as shown.
